UNITED STATES PATENT OFFICE.

PERCY HOLBROOK, OF NEW YORK, N. Y., ASSIGNOR TO WEBER RAILWAY JOINT MANUFACTURING COMPANY, OF NEW YORK, N. Y., A CORPORATION OF WEST VIRGINIA.

INSULATED JOINT.

SPECIFICATION forming part of Letters Patent No. 771,983, dated October 11, 1904.

Application filed December 28, 1903. Serial No. 186,789. (No model.)

To all whom it may concern:

Be it known that I, PERCY HOLBROOK, a citizen of the United States, and a resident of the borough of Manhattan, city, county, and State 5 of New York, have invented certain new and useful Improvements in Insulated Joints, of which the following is a specification accompanied by drawings.

This invention relates to insulated joints; 10 and its objects are to improve upon the construction of such joints and obtain improved insulating qualities and improved means for maintaining the insulation in position beneath the rails.

15 Further objects of the invention will hereinafter appear; and to these ends the invention consists of joints for carrying out the above objects embodying the features of construction, combination of elements, and arrangement of parts, substantially as hereinafter fully described and claimed in this specification and shown in the accompanying drawings, in which—

20 Figures 1 and 2 are transverse sectional views of joints embodying the invention. Fig. 25 3 is a plan view of a joint. Fig. 4 is a side elevation of a joint.

25 Referring to the drawings, A and B represent the meeting ends of rails, and C is a rail-chair having a base D and an upright E. Arranged along the webs of the rails are the filling-blocks F, Fig. 2; of suitable material, as wood. At one side of the joint opposite the upright E is the metallic band or strap G. 30 Suitable bolts H are provided for holding the parts of the joints together, and a sufficient number of said bolts are insulated from the upright E and the strap G to protect the electric continuity of the rails. In this instance 35 the usual insulating-sleeves I and washers J are provided for the bolts.

40 In Fig. 1 instead of insulating-blocks F at each side of the rails filling-pieces K are provided in the form of spools, which may be of any suitable material as metal or insulation. 45 In this instance they are shown as metal, and hence are insulated from the upright E and strap G.

The insulation beneath the bases of the rails, or beneath at least one of them, consists 50 of a plurality of layers of material, as shown. If desired, these layers of material may be secured together by the insulating-rivets L. As shown, the uppermost layer O consists of a flat sheet of fiber or other suitable material, 55 while the undermost layer P in Fig. 1 extends upwardly so as to be clamped tightly between the parts of the joint to hold the insulation in position. According to this invention one layer of the insulation is extended upwardly 60 and clamped between portions of the joint at the inside of the joint on the inner side of the rail-webs. By the "inside" of the joint is meant that side of the joint which faces the opposite rails. Those portions of the joint which 65 face outwardly away from the track are ordinarily called the "outer" sides of the joints, while those portions which face inwardly toward each other when the joints are in track are called the "inside" portions of the joint. 70 In ordinary construction the upright of the angle-chair is placed upon the outside of the rails, while the strap or bolt-plate is on the inside, or, in other words, on that side of the rails along which the wheel-flanges pass. In Fig. 1 75 the undermost layer P is clamped between the strap G and the filling-pieces K, which affords a suitable construction. The undermost layer P may be of the same thickness as the upper layer O, or it may be of different 80 thickness, and both layers may consist of fiber or any other suitable insulation, as insulating-cloth, or one of the layers, as the upper layer, may consist of fiber and the lower one may consist of thin insulating-cloth. In 85 Fig. 2 the undermost layer O consists of a flat sheet, while the uppermost layer P is extended upwardly to be clamped between the parts of the joint. In Fig. 2 said upper layer is clamped between one of the filling-blocks F 90 and the metal band G.

95 One of the great advantages of securing the insulation, as shown in Figs. 1 and 2, resides in the fact that the insulation may be repaired or replaced by simply removing the bolts and the metal band G. When this is

done, the insulation may be slipped from under the rails. Hence greater accessibility than heretofore is afforded to the insulation. It is preferable to use two layers rather than 5 one or a plurality of layers, because the wear upon the insulation beneath the rails is very great and a possibility of short circuits is very greatly guarded against according to this invention. In all of the figures the insulating 10 layer, which is extended upwardly to be clamped between parts of the joint, serves to hold the insulation in position, and this is true whether the insulating-rivets are provided or not—that is to say, it is found that 15 even without any rivets L one layer of insulation will not slip materially without the other, and since one is held both are held.

Obviously some features of this invention may be used without others, and the invention 20 may be embodied in widely-varying forms.

Therefore, without limiting the invention to the constructions shown and described nor enumerating equivalents, I claim, and desire to secure by Letters Patent, the following:

25 1. An insulated rail-joint, comprising the meeting ends of rails and bolt-plates for maintaining them in alinement, insulation beneath the base of at least one of the rails, said insulation comprising a plurality of layers, one 30 of said layers being extended upwardly and clamped against the bolt-plate at the inside of the joint, said clamped portion of the insulation being situated inside of the rail-webs in contradistinction to being secured at a por-

tion of the joint outside of the rail-webs, for 35 substantially the purposes set forth.

2. An insulated rail-joint, comprising the meeting ends of rails, a rail-chair having a base and an upright, means for maintaining the rails in alinement, a metallic bar on the 40 side of the joint opposite the upright, insulation beneath the bases of at least one of the rails, said insulation being extended upwardly and clamped against the metallic bar on the inside of the joint, whereby said insulation 45 may be inspected and removed by loosening the bolts without disturbing the rail-chair, for substantially the purposes set forth.

3. An insulated rail-joint, comprising the meeting ends of rails, a rail-chair having a 50 base and an upright, means for maintaining the rails in alinement, a metallic bar opposite the upright, insulation beneath the base of at least one of the rails, said insulation comprising a plurality of layers of material, one 55 layer consisting of a flat sheet, and the other layer being provided with an upwardly-extending portion clamped against the metal bar at the inside of the joint, for substantially the purposes set forth. 6c

In testimony whereof I have signed this specification in the presence of two subscribing witnesses.

PERCY HOLBROOK.
